UNITED STATES PATENT OFFICE

RICHARD H. STEVENS, OF BALTIMORE, MARYLAND, ASSIGNOR TO BETHLEHEM STEEL COMPANY, A CORPORATION OF PENNSYLVANIA

VENTILATOR

Application filed April 17, 1931. Serial No. 530,871.

My invention relates to the ventilation of buildings and more particularly to that type of building, such as enclosed steel mills, foundries, chemical plants, and the like, wherein vitiated air, noxious or offensive gases, vapors, and the like are developed and require to be removed as rapidly and as continuously as possible.

The object of this invention is to provide in buildings means which acting in conjunction with natural air currents obtains the rapid and continuous withdrawal from said buildings of vitiated air, gases, vapors and the like, regardless of in what direction the natural air currents are moving.

The novel features of my invention will be more fully understood from the following description and claims taken with the drawing in which:

Fig. 1 illustrates diagrammatically a conventional type of mill building embodying my invention;

Fig. 2 is a cross section taken on the line 2-2 in Fig. 1;

Fig. 3 is a cross section taken on the line 3-3 in Fig. 1; and

Fig. 4 is an end elevation detail in cross section similar to Fig. 3 showing a modification of the louvred openings.

Referring to the drawing: 10 designates the main body of the building from which vitiated air, gases and vapors, or the like, is to be drawn by the action of the structure embodying my invention in conjunction with the natural air currents. 11 shows the embodiment of my invention superposed along the ridge of the main building roof 12, and comprises a continuous secondary roof 13 in spaced relation to the main building roof 11.

The spaced relation is maintained by the structural elements comprising the vertical walls of the apertured chambers 14, 15, and 16, together with the baffle walls 17. The apertured chambers 14 and 16, are the end chambers, and have louvred apertures 18 and 19 only on their inner transverse walls, the other three walls being closed; while the intermediate apertured chamber 15 has louvred apertures 20 and 21 in both transverse end walls. Though I show only one intermediate

apertured chamber 15, it is intended that there shall be as many such chambers as the size and type of building shall require. Also, I show louvred apertures as the preferred form, though any other type of aperture may be used, such as plain openings, screened openings, latticed openings, or the like, that will permit of a flow-through of air, gases, or vapors. Each apertured chamber 14, 15, and 16 is in communication with the interior of the main building 10 by means of apertures 22 in the main roof. It will be noted that the baffles 17 divide the intervening space between the transverse end walls of the apertured chambers into two transverse chambers 23 and 24 entirely open at both outer ends.

Fig. 4 shows a modification in the arrangement of the louvred openings. The louvred openings 25 are horizontal with openings 26 between the topmost louvre and the roof 13. Below the line of ridge of roof 12 are closed sections 27.

From the above description it is seen that I provide in a building between two superposed continuous roofs a series of chambers, each in communication with the interior of the main building by means of apertures in the main roof; and which chambers have their opposed transverse walls apertured preferably with louvred openings. Also, I have shown that by this construction I get clear passageways transversely of the roofs, which are formed of the two roofs and two opposed transverse walls; and that each of these passageways I divide in two by means of a baffle-plate placed transversely of the roofs. With this arrangement the natural outdoor air currents may approach the building from any direction, but at each transverse passageway, by reason of the transverse baffle-plate, the air currents are deflected and are caused to flow parallel to, and by, the louvred apertures of the opposed end walls of the adjacent chambers. This through-flow of the natural air currents past the louvred apertures of the adjacent chambers tends to create a vacuum within the latter, and this in turn acts to draw upon the fluid contents of the interior of the main building; and, since the air currents are practically con-

stant, there is a practically constant movement of the air within the building upward and outward through the louvred end walls. Outdoor air to replenish that withdrawn is 5 admitted to the building through the usual windows, doors, ducts, or the like, not shown on the drawing.

From the foregoing description it will be seen that I have devised means applicable to 10 buildings and which means are particularly suitable to maintain thorough and practically constant ventilation of the building to which it may be applied.

While I have shown my invention in but 15 one form, it will be obvious to those skilled in the art that it is not so limited, but is susceptible of various other changes and modifications without departing from the spirit thereof, and I desire, therefore that only such 20 limitations shall be placed thereupon as are imposed by the prior art or as are specifically set forth in the appended claims.

Having thus described my invention, what 25 I claim as new and desire to secure by Letters Patent is:

1. A ventilator for a building having an apertured roof comprising, two monitors each superposed over an aperture in the roof of said building, a vertical transverse baffle, 30 said monitors having their inner oppositely disposed transverse walls apertured and in spaced relation to one another and to said baffle, and a secondary roof continuous over said monitors and said baffle.

35 2. A ventilator for a building having a main roof comprising, a continuous roof in spaced relation to the main roof of the building, a series of monitors alternating with a series of vertical transverse baffles in spaced 40 relation one to another, the structural elements of which maintain the spaced relation between the two roofs, and each of the monitors communicating with the body of said building by means of apertures in the main roof and having apertures in the walls which are directed toward said baffles.

45 3. A ventilator for a building having an apertured roof comprising, two monitors each superposed over an aperture in the roof of said building, a vertical transverse baffle, said monitors having their inner oppositely disposed transverse walls apertured and in spaced relation to one another and to said baffle, and the said monitors and the spaces 50 between the said monitors and the said baffle each having a roof thereover.

55 4. A ventilator for a building having a main roof comprising, a series of monitors alternating with a series of vertical transverse baffles in spaced relation one to another, each of the said monitors and each of the spaces between the said monitors and the said baffles having a roof thereover in spaced relation to the main roof of the building, the 60 structural elements of the said monitors and

of the said baffles maintaining the spaced relation between the first mentioned roof and the main roof of the building, and each of the said monitors communicating with the body of the said building by means of apertures in the main roof and having apertures in the walls which are directed toward the said baffles.

In testimony whereof I hereunto affix my 70 signature.

RICHARD H. STEVENS.
